LOCK FOR EXTENSION TABLES

Filed Sept. 21, 1948

Fig. 1.

UNITED STATES PATENT OFFICE

2,583,282

LOCK FOR EXTENSION TABLES

Philip M. Virtue, Los Angeles, Calif., assignor to
 Virtue Bros. Mfg. Co., Los Angeles, Calif., a
 corporation of California

Application September 21, 1948, Serial No. 50,297

2 Claims. (Cl. 311—49)

1

This invention relates to a lock for extension tables and has for an object to provide inexpensive and relatively simple means effecting automatic locking or latching of the table parts and also ready release of said means to free said parts for extension.

Another object of the present invention is to provide novel means of the character indicated that are inexpensively formed of wire.

Another object of the invention is to provide locking means comprising similar oppositely formed wire latching units and to interconnect said units with an easily reached, although unseen, connecting wire that is adapted to be pulled to effect release of the latching units simultaneously.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describe one embodiment of the present invention, which is given by way of illustration or example only.

In the drawings, like reference characters designate similar parts in the several views.

Fig. 1 is a bottom plan view, partly broken away of an extension table equipped with the locking means of the present invention, the leg supports of the table being omitted.

Fig. 2 is an enlarged sectional view as taken on line 2—2 of Fig. 1.

Fig. 3 is a vertical sectional view as taken on line 3—3 of Fig. 2.

Fig. 4 is a further enlarged fragmentary bottom plan view showing one of the locking or latching units in released position.

The table that is illustrated conventionally comprises relatively slidable top sections 5 and 6 that meet at a central transverse joint 7, said sections being interconnected by rails 8 and 9, the former fixed with section 5 and the latter with section 6. The rails maintain alignment of the sections and are connected to slide relatively by bolts or rollers not shown and operating in elongated slots 10 that are formed, at least in rails 9. A table, thus constructed, will retain its closed position with the sections 5 and 6 abutting at joint 7 if rails 9, that are fixed with section 6,

2

are locked or latched to section 5. The present locking means is provided to effect such a releasable locking of the sections.

Said locking means is shown as comprising, generally, two latch units 11 carried on the under-side of section 5, one associated with the end of each rail 9, and a transversely disposed wire 12 interconnecting said units, each unit having separable locking engagement with an abutment 13 defining the adjacent end of the slot 10 of each said rails 9. Inasmuch as the units 11 are alike except for being of the opposite hand, the following description of one will serve to describe the other.

15 The unit 11 is formed of a single length of reasonably resilient wire, the same generally comprising a spring arm 14, a fixed arm 15, a coiled connection 16 for said arms, and an extension 17 for limiting movement of arm 14 during release movement thereof to obviate undue strain being placed on said arm 14.

20 The unit 11 is affixed to the under-side of section 5 as by a screw or the like 18, the head of which engages a bight 19 formed in arm 15 thereby fastening said arm 15 flat against the bottom surface of said table top section. A second point of securement—one that rather holds the unit against rotation around screw 18—comprises a stud or pin 20 that is fixed to the table section and extends through coiled connection 16.

25 The screw 18 and pin 20 are so associated with the adjacent end of rail 9 that, with the table sections abutted, an offset latch portion 21, formed in an intermediate part of arm 14, engages end abutment 13 of said rail, the offset portion entering slot 10. The portion 22 that connects portion 21 with coil 16 is resiliently carried by said coil and normally seeks a position urging portion 21 into slot 10. Beyond offset portion 21, arm 14 is provided with an angled end 23 that terminates in a ring or eye 24. While arm 14, in itself has some resiliency, the same has little tendency to flex except about coil 16 as a fulcrum. The sloping or angled end 23 is 30 adapted to be engaged by end 25 of rail 9 when the table, from extended position, is being retracted or closed, said portion 23 being urged progressively further inward by end 25 and then, as offset portion aligns with slot 10, the arm springs from the inwardly flexed position of Fig. 4 to table-locking position of Fig. 1.

35 The fixed arm 15, for stability of the unit, is formed of two relatively angled portions 26 and 27 that lie flat against the under surface of section 5. The bight 19 is formed at the end of

portion 27 and is then extended at 28 to connect with extension 17. The latter comprises a downwardly directed portion 29 that is in the path of movement, while being flexed, of portion 22 of arm 14. Thus, should said arm 14 be unduly flexed, portion 29 will form a resilient stop that counteracts such excess flexure. The bottom end of portion 29 is bent back in the direction of part 28 to form a portion 30 between which and said part 28, arm 14 is free to move. Thus, any force tending to flex arm 14 downward rather than horizontally, is counteracted by portion 30 that intercepts said arm and guards it against such abnormal flexure.

The wire 12 is formed with an eye 31 at each end for connection to the eyes 24 of units 11. With the table contracted, as shown, a person simply reaches beneath top section 5 and grasps and pulls on any portion of wire 12 to cause retraction of arms 14 from engagement with rails 9. The table sections may now be separated. An unduly hard pull will be counteracted by portions 29 which also serve to equalize the flexure of the arms. Even if one arm should release first, it will be brought to a stop and the other arm will then release. Any tendency toward a downward pull on wire 12 is counteracted by portions 30. As above indicated, the separated sections may then be brought into abutment and automatically re-latched.

While the invention that has been illustrated and described is now regarded as the preferred embodiment, the construction is, of course, subject to modifications without departing from the spirit and scope of the invention. It is, therefore, not desired to restrict the invention to the particular form of construction illustrated and described, but to cover all modifications that may fall within the scope of the appended claims.

Having thus described my invention, what I claim and desire to secure by Letters Patent is:

1. In a lock for an extension table having relatively slidable top sections, two spaced latch units mounted on the under surface of one top section for releasably engaging the other top section, and a flexible and integral connecting member for manual flexing actuation of said units, each latch unit comprising an integral length of spring wire formed to have a spring arm, a fixed arm, and a resilient coiled con-

nexion for said arms, and said spring arm being formed with an offset latching portion adapted to releasably engage said other top section and with an end extension terminating in an eye 5 effecting connection with said flexible connection member, said end extension being angled with respect to the general longitudinal disposition of said spring arm to provide a portion adapted to be engaged by said other top section to effect 10 inward flexing of the spring arm upon movement of said table sections toward each other.

2. In a lock for an extension table having relatively slidable top sections, two spaced latch units mounted on the under surface of one top section for releasably engaging the other top section, and a flexible and integral connecting member for manual flexing actuation of said units, each latch unit comprising an integral length of spring wire formed to have a spring arm, a fixed arm, and a resilient coiled connection for said arms, an integral resilient flexure-limiting stop for said spring arm and formed as an extension of said fixed arm, said stop comprising portions limiting both inward and 15 downward flexure of said spring arm, and said spring arm being formed with an offset latching portion adapted to releasably engage said other top portion and with an end extension terminating in an eye effecting connection with said 20 flexible connecting member, said flexure-limiting stop being positioned in the path of movement of the spring arm to limit the movement thereof when being flexed by the connecting member.

PHILIP M. VIRTUE.
